DIRECT DRIVE PUSH BUTTON ROTARY SWITCH
Richard Terral Jeans, San Diego County, Calif., assignor
to Cubic Corporation, San Diego, Calif.
Filed Aug. 6, 1964, Ser. No. 387,847
7 Claims. (Cl. 200—11)

The present invention relates to switches and more particularly to multi-position switches.

In some types of electrical equipment, it is necessary to supply an electrical signal having a magnitude proportional to a particular value. By way of example, in a control system, it may be necessary to provide a control signal proportional to the magnitude at which a function should be maintained.

One means for providing such signals is to employ a so-called thumb wheel type of rotary switch. Such a switch employs a number wheel having a sequence of indicia such as letters or numbers spaced around its periphery. The wheel is manually rotated by pushing the wheel with the operator's thumb or finger until the desired number is exposed. By moving the number wheel, one or more electrical contacts are actuated to establish and maintain electrical circuits which produce a signal corresponding to the setting of the wheel.

More recently, it has been proposed to provide thumb wheel switches wherein the movement of the number wheel is controlled not by frictional engagement of the operator's thumb or other digit but by a manually actuated push button. An example of this type of thumb wheel switch is disclosed in United States Patent No. 3,104,299 filed February 8, 1962, in the name of Koci, et al., and entitled "Actuating Mechanism for A Thumb Wheel Type of Switch." The number wheel is enclosed in a housing having a window in the front thereof whereby only a single number at a time registers with a window so as to be exposed to view. A push button is mounted on the housing and is operatively connected to the number wheel. When it is desired to rotate the wheel and advance the exposed number, the push button is manually depressed. Such a movement of the wheel is effective to stretch a spring and set or cock a ratchet mechanism. When the push button is released, the spring causes the ratchet mechanism to advance the number wheel by an increment corresponding to one number.

Although such an advancing mechanism may be acceptable for many applications, it has several limitations. For example, since the wheel is advanced by the spring, the operator has no "feel" of the wheel rotating. Very frequently, the operator does not carefully observe the exposed numbers as the wheel is advanced. Instead, the operator merely pushes the button the number of times required to advance the number wheel through the required number of increments. In the event the number wheel does not advance properly, for example, the push button is not depressed adequately or the spring and ratchet mechanism "hangs up," the operator may not sense or feel this failure whereby an error will be produced unless he carefully observes the exposed indicia.

It should also be noted that under some circumstances the number wheel may become stuck and fail to rotate. Since the force applied to the wheel is limited by the tension in the spring, it is impossible to overcome the obstruction and force the wheel to rotate by more firmly pressing the push button. As a result, it becomes necessary to entirely dismantle the switch to free the wheel.

The prior art switch further includes a wafer blank secured to the outside of the housing. A circuit printed on the exterior of the wafer blank provides a plurality of electrical contacts corresponding to the numbers on the wheel. A movable contact interconnected with the number wheel projects through the wafer blank and rides

around the exterior of the wafer blank and across the various contacts formed by the circuit. Since the movable contact must project through the wafer blank, it is extremely difficult, if not impossible, to completely seal the electrical contacts in the switch and isolate them from the ambient environment. The exposed contacts are hazardous since they may produce sparks that may ignite an explosive atmosphere. Also, it is possible for dirt and dust to collect on the contacts and interfere with the proper operation of the switch. In addition, it is necessary to provide a substantial clearance space for the contact adjacent to the side of the switch. As a consequence, if several switches are juxtaposed to produce a multi-digit number, the digits are widely spaced and not easily read.

15 The present invention overcomes these difficulties. More particularly, the present invention provides a switch having a number wheel that may be advanced by manually depressing a push button. The push button is positively interconnected with the number wheel by means that are effective to provide a direct drive between the push button whereby the force that rotates the wheel is supplied directly by the operator and provides a "feel" that will insure the operator being fully aware of any failure of the number wheel to advance.

20 25 In a preferred embodiment of the switch, a housing is provided which has an enlarged space or cavity for receiving an indicator wheel. The space forms an enlarged opening in the side of the housing so as to permit access to the indicator wheel. A push button which protrudes from the housing is interconnected with a pawl that rides over cam or ramp surfaces on the wheel. When the push button is depressed, the pawl locks against a ramp and forces the wheel to advance through a suitable increment 30 35 and know whether it has advanced.

An imperforate cover is attached to the housing so as to extend across the opening formed by the space and is adapted to completely seal the space and indicator wheel. A circuit is printed on the inside surface of the cover so as to form an annular array of fixed electrical contacts that are sealed inside of the housing. A movable contact is mounted on the wheel and is carried thereby so as to be completely sealed in the housing. The movable contact slides across the fixed contacts whereby an electrical circuit is established and maintained that corresponds to the indicia displayed by the indicator wheel. The printing forming the circuit extends across the surface of the cover and between the housing and the cover to provide a plurality of external contacts.

40 45 Therefore, it is an object of the present invention to provide a switch which is compact and which may be combined with similar switches to produce a display wherein the characters are all closely spaced together.

It is another object of the present invention to provide 50 55 a switch wherein all of the electrical contacts and moving parts are contained inside of the switch whereby the switch may be completely sealed without increasing the bulk of the switch or the spacing of adjacent switches, to prevent the leakage of any explosive or corrosive gases into the region of the electrical contacts and will prevent dirt and dust accumulating on the contacts whereby the switch may be employed in any desired environment.

These and other features and advantages of the present invention will become readily apparent from the following detailed description of a switch employing one embodiment of the present invention, particularly when taken in connection with the accompanying drawings wherein like reference numerals refer to like parts and wherein:

FIGURE 1 is a front elevational view of a group of switches embodying the present invention, said switches being mounted adjacent to each other to form a multi-digit display;

FIGURE 2 is a side elevational view of the "inside" of a cover employed in one of the switches of FIGURE 1;

FIGURE 3 is a side view of a portion of the operative elements of the switch;

FIGURE 4 is a top plan view of the switch; and

FIGURE 5 is a side elevational view of the switch with the cover of FIGURE 2 removed.

Referring to the drawings in more detail, the present invention is particularly adapted to be embodied in a rotary switch 10 of the so-called thumb wheel variety. The switch 10 includes a front or face 12 having a window 14 which is effective to display a character or indicia such as a letter, number, etc., corresponding to the setting of the switch 10. In addition, the switch 10 may be arranged with a plurality of similar switches to form an array of juxtaposed windows 14 whereby the indicia exposed through the windows 14 will provide a multi-digit display.

The switch 10 may include means that enclose all of the operative parts of the switch 10. In the present instance, these means include a housing 16 that is a single integral structure. The housing 16 may be formed by any suitable means such as die casting, or machining from a solid member.

The present housing 16 is of a generally rectangular configuration having a substantially planar side wall 18. For reasons that will become more apparent subsequently, this side wall 18 is preferably made very thin. In addition to the side wall 18, the housing 16 includes edge walls 20, 22, 24 and 26, best seen in FIG. 5, that extend completely around the entire periphery of the side wall 18. The lateral widths of the edge walls 20 to 26 are preferably only slightly greater than the width of the indicia to be displayed.

Referring now to FIG. 5, it may be appreciated that the side wall 18 and the edge walls 20 to 26, will at least partially define a cavity or space 28 which is accessible through an enlarged opening in the side of the housing 16. The cavity or space 28 may be of any desired size and shape. However, it has been found desirable for the space 28 to have a width that is equal to the height of the edge walls, i.e. slightly greater than the width of the indicia to be displayed and a shape that is substantially circular.

The front of the edge wall 20 may be substantially plane whereby it will provide a face 12 that conforms to a plane or similar structure upon which the switch 10 is mounted. The center portion of the front wall 20 may include an opening or window 14. This window 14 extends completely through the edge wall 20 and opens into the space 28. As a consequence, an operator positioned in front of the switch 10 may look through the window 14 and observe the contents of the space 28.

In addition, the housing 16 may include means for controlling the operation of the switch 10. In the present instance, these means include an extension 32 which projects outwardly from the housing 16. By way of example, this extension 32 may be disposed to project forwardly from the face 12 just below the window 14. This will insure the extension 32 from being conveniently disposed to an operator observing the window 14.

A passage may be provided axially through the extension 32 and which opens into space 28. The means 34 for controlling the operation of the switch 10 may be disposed in the passage inside of extension 32. One end of the means 34 may project from the end of the extension 32 so as to be convenient to an operator while the other end of the control means may extend into the space 28 so as to operate the switch 10.

An indicia or number wheel 36 may be disposed in the space 28 as seen in both FIGS. 3 and 5. The wheel 36 includes a periphery or rim 38 that extends completely around the wheel 36 so that it will be aligned with the window 14. The axial dimension of the rim 38 is approximately equal to the depth of the space 28 or to the height of the edge walls 20 to 26. This dimension is

normally just slightly less than the height of the walls whereby a clearance space will be provided that is just adequate to permit the wheel 36 to rotate.

The center of the wheel 36 includes a hub 40 that has an axial dimension that is approximately equal to the width of the rim 38. The hub 40 includes a passage that extends axially therethrough. This passage is adapted to receive a support pin 42. This pin 42 may be mounted on the side wall 18 or secured thereto. The pin 42 rotatably supports the number wheel 36 so that the wheel 36 will be free to rotate inside of the housing 16. As the wheel 36 rotates, the rim 38 will move past the window 14 so that various portions will be visible.

The rim 38 of the wheel 36 has a plurality of portions such as flat spots 44 that are adapted to carry characters or indicia, printed or engraved thereon. Although any type of indicia such as letters, etc., may be employed, in the present, a series of numbers are employed. Accordingly, the present number wheel 36 includes eleven faces or flats 44. One of these is blank and has no number thereon. The remaining ten flats 44 are numbered consecutively from 0 through 9.

In FIG. 3, the means 34 for advancing the wheel 36, and for locking it in position, are best seen. Although any suitable means may be employed, in the present instance, they include a plurality of cam surfaces such as ramps 46. A separate ramp 46 is provided for each of the indicia or flats 44 on the wheel 36.

Each ramp 46 extends radially outwardly from the hub 40 towards the rim 38, and each includes an inclined surface 48 that slopes circumferentially around the wheel 36 and is separated from the adjacent surfaces by radial shoulders 50. This side of the wheel 36 is adapted to be disposed adjacent to the side wall 18 whereby ramps 46 will be disposed between the side wall 18 and the wheel 36.

A thin flat member 52 similar to a shim or washer may be mounted on the hub 40 or the pin 42 whereby the washer member 52 will be free to rotate relative to the wheel 36. A resilient extension such as a finger 54 may be provided on the washer member 52. The end of this finger 54 is adapted to slide across the inclined surfaces 48 and successively drop behind the radial shoulders 50 whenever the washer member 52 rotates in one direction relative to the wheel 36. However, whenever the washer member 52 endeavors to rotate in the opposite direction, the finger 54 will become lodged behind one of the radial shoulders 50 and force the wheel 36 to rotate therewith in the same direction.

The flat washer member 52 may be secured to the control means 34 that are disposed in the extension 32 projecting from the face 12 of the housing 16. These control means include a pin 56 that is slidably disposed in the extension 32 whereby the outer end of the pin 56 will project beyond the end of the extension 32. The outer end may be slightly enlarged so as to form a push button 58 that is suitable for normal actuation. A spring 60 may be coiled around the pin 56 so as to normally bias it into a fully extended position, as best seen in FIG. 5.

The inner end of the pin 56 may be slightly flattened and interconnected with the flat washer member 52 by a link 62. The link 62 is preferably very thin so that it is free to pass between the wheel 36 and the side wall 18 even though clearance space is provided.

It may be appreciated that pushing inwardly on the push button 58 will be effective to cause the link 62 to rotate washer member 52 in a counter-clockwise direction (as seen in FIG. 3). When rotating in this direction, the finger 54 will engage a shoulder 50 and rotate the wheel 36 therewith. If the push button 58 is depressed through a full stroke, the wheel 36 will be rotated through an arc equal to the arc subtended by a flat 44.

When the push button 58 is released, the spring 60 will force the pin 56 to return to its extended position. During such movement, the washer member 52 will ro-

tate clockwise, whereby the finger 54 will slide across an inclined surface 48 and drop behind the next succeeding shoulder 50.

A thin leaf spring 64 may be provided to prevent the wheel 36 rotating in a reverse direction when the push button 58 is released. The opposite ends of the spring 64 are disposed in pockets 66 that are recessed into the sides of the housing 16. The spring 64 is sufficiently thin to fit between the rim 38 and the side walls 18. An intermediate portion of the spring 64 projects away from the side wall 18 so as to engage the ramp 46.

When the washer member 52 rotates so as to advance the wheel 36 by one increment, the free end of the spring 64 will pass over a shoulder 50 and engage it. As a consequence, when the push button 58 is released, the free end of the spring 64 will become lodged behind a shoulder 50, whereby the wheel 36 will be prevented from rotating in the reverse direction.

The spatial relationships between the spring 64 and shoulder 50 are arranged so that a flat 44 on the rim 30 will be precisely aligned with the window 14. As a consequence, one particular indicia or number will be precisely aligned with the window 14 and readily visible to an operator disposed in front of the switch 10.

The space 28 inside of the housing 16 may be sealed by means of a cover 68. The cover 68 is a flat or planar member of substantially uniform thickness. For reasons that will become apparent subsequently, it is desirable that this member 68 be as thin as possible. The cover 68 is secured directly to the edge walls 20-26 by any suitable means. It is preferable that the cover 68 be attached so as to provide a dust and/or gas-tight seal. This will prevent any of the surrounding atmosphere entering the interior 28 of the switch 10.

With reference next to FIG. 2, the cover 68 has a rectangular shape that is approximately the same size as the housing 16, whereby two sides will be substantially flush with the exteriors of the top and bottom edge walls 22 and 24. For esthetic reasons, it has been found desirable to provide a small extension 70 on the front wall 20. This extension 70 is equal to the thickness of the cover 68 and is effective to conceal the cover 68 from view. The rear edge of the cover projects slightly beyond the exterior of the housing so as to provide a lip 72.

Electrical contacts may be provided on the cover 68 to produce electrical signals corresponding to the angular position of the wheel 36, i.e. the indicia exposed through the window 14. In the present instance, these electrical contacts are provided on the inside surface of the cover 68.

Although these contacts may be provided by any suitable means, in the present instance, they are in the form of a so-called printed circuit 74. Such a circuit is formed by electrically conductive strips that are bonded directly onto the surface of the cover 68. These strips are very thin and by way of example, may be similar to a copper foil or leaf.

One portion of the circuit 74 includes a continuous circular portion that forms a "fixed" contact ring 76. This circular contact ring 76 is preferably positioned so that it will be substantially concentric with the axis of rotation of the wheel 36. This circular contact ring 76 may correspond to an electrical common or ground contact.

Another portion of the circuit 74 includes an annular array 78 of fixed contacts. This array 78 is also concentric with the fixed contact ring 76 and includes a separate segment 80 for each flat 44 or indicia provided on the periphery of the wheel 36.

A separate electrical lead 82 may be provided for each of the contacts 76 and 80. These leads 82 are disposed substantially parallel to each other and extend from the contacts 78 and 80 across the cover 68 to the lip 72. The cover 68 may be fastened directly to the edge walls 20 to 26 with the leads compressed between the edge

walls 26 and the cover 68. The exposed portions 84 of the leads 82 on the lip 72 will provide electrical contacts that may be connected to any suitable electrical circuit. It should be noted that the leads 82 are very thin and, as a consequence, will not interfere with the seal between the cover 68 and the edge wall 26.

Turning to FIG. 5, a suitable movable contact 86 may be mounted on the wheel 36 so as to engage the fixed contacts 76 and contact ring 80. This will be effective to establish an electrical circuit between the fixed contacts 76 and 80 uniquely corresponding to the angular position of the wheel 36 and the exposed indicia.

In the present instance, the movable contact 86 includes an electrically conductive spring clip 88 which is adapted to be mounted on the wheel 36. The wheel 36 may be recessed to provide a pocket 90 into which the clip 88 will just fit. It will be seen that this will be effective to lock the movable contact 86 onto the wheel 36 so that it will be carried thereby.

The clip 88 includes two separate fingers 92 and 94 that project from the clip 88 at two spaced points. The first finger 92 is positioned to engage the continuous or ground contact ring 76. The second finger 94 is positioned to engage a single contact 80 at a time in the array 78. The movable contact 86 will thus form an electrical bridge between the contact ring 76 and one of the fixed contacts 80, corresponding to the position of the wheel 36.

In order to use the present switch 10, it may first be assembled by placing the pin 56 in the extension 32 and positioning the washer member 52 concentrically about the pin 42. The leaf spring 64 is then positioned with the opposite ends thereof in the pockets 66. Following this, the number wheel 36 is placed around the pin 42 so that the ramps 46 will co-act with the spring 64 and the finger 54 on the washer member 52. The movable contact 86 is then seated in the recess 90 on the wheel 36 and the cover 68 attached.

At this point, the fingers 92 and 94 on the movable contact 86 will engage the fixed contacts 76 and 80 and form a continuous circuit therebetween. A plurality of electrical conductors may be attached between any desired external circuits and the contacts formed by the exposed ends 84 of the leads 82. A continuous electrical path will then be formed between the portion of the circuit connected to the common connector and the portion connected to the connector corresponding to the position of the number wheel 36 and the indicia exposed through the window 14.

To change the electrical connections to the external circuit in order to correspond to another indicia, the operator may merely depress the push button 58. Each time the push button 58 is depressed, the resilient finger 54 on the washer member 52 will become lodged behind one of the shoulders 50. If the operator depresses the push button 58 to the full length of its stroke, the washer 52 will rotate through an increment that is equal to the increment between the successive flats 44. As a consequence, even though the operator may not be viewing the window 44, he will know, by the feel of the button 58, that the number wheel 36 has rotated.

In the event the wheel 36 is jammed or "hung up" or for some reason does not rotate, the operator will quickly recognize this condition since the push button 58 will not travel over its full stroke. However, since a direct and positive drive is provided between the push button and the wheel 36, if the operator so desires he can depress the push button 58 with added force and, unless the malfunction is serious, the wheel 36 can be forced to rotate.

After the wheel 36 has been rotated into its new position, the fingers 92 and 94 on the movable contact 86 will have established a new electrical circuit, corresponding to the newly exposed indicia.

It may be observed that all of the moving parts and all of the "make" and "break" electrical contacts of the switch 10 are enclosed within the space 28. Since the

conductors 82 are extremely thin, electrically-conductive strips and can be made flush with the surface, they will not have an adequate thickness to interface with an air-tight seal between the cover 68 and the housing 16. As a consequence, it will be possible to completely isolate 5 the operative parts from the surrounding atmosphere. If there are any dust particles, moisture, etc., in the atmosphere, it will be impossible for them to enter into the space 28 and interfere with the operation of the switch 10.

To further increase the effectiveness of the sealing action, a flexible boot 96 consisting of an elastomeric material, such as rubber or the like, may be secured to the exterior of the extension 32 so as to completely surround the push button 58. Since the boot 96 is very flexible, it will not interfere with the manual actuation of the 15 push button 58, and will prevent "leakage" around the push button 58.

In the event, it is desired to provide a multidigit display, a large number of identical switches 10 may be employed. As best seen in FIG. 1, an array of switches 20 may be disposed in a vertical side-by-side arrangement with all of the windows 14 aligned with each other. Since all of the operative elements of the switch 10 are sealed inside of the housing 16, the switches 10 may be placed 25 in intimate contact with each other. In addition, since 25 the side wall and cover 68 are very thin, the wheels 36 will be closely spaced. This, in turn, will be effective to allow the windows 14 and the indicia therein to be 30 closely spaced whereby the indicia will form a single, continuous, multi-digit display.

While only a single embodiment of the present invention has been disclosed, it will be readily apparent to those skilled in the art that numerous changes and modifications may be made thereto without departing from the invention. Accordingly, the foregoing description and drawings are for illustrative purposes only and are not to limit the scope of the invention which is defined only by the claims which follow.

What is claimed as new is:

1. A switch of the class described including the combination of:
  - a housing at least partially enclosing a space;
  - a cylindrical number wheel rotatably disposed in said housing;
  - a cylindrical rim on the wheel;
  - a series of indicia spaced around the rim of the wheel;
  - a window in said housing aligned with the rim of the wheel, said window being positioned to permit viewing of only one indicia at a time;
  - a separate ramp on said wheel for each indicia, said ramps being radially disposed around said wheel;
  - a push button reciprocally mounted on the housing;
  - a detent interconnected with said push button, and effective to engage a ramp and advance the wheel and position the succeeding indicia in registry with the window whenever said push button is depressed; and
  - a second detent effective to ride over said ramp when said push button is depressed and preventing said wheel rotating in the reverse direction.

2. A switch of the class described including the combination of:
  - a housing member at least partially enclosing a space;
  - a wheel rotatably disposed in said space and including an annular rim;
  - a plurality of cam surfaces disposed between the rim and the center of the wheel;
  - a series of indicia circumferentially spaced around the rim of the wheel;
  - a cover member secured to said housing member and enclosing said space and the wheel therein;
  - a window in said housing member positioned to register with only one of the indicia at a time;
  - an annular array of contacts on one of said members,

said array including a separate contact for each one of said series of indicia;

a movable contact mounted on said wheel and including at least one portion that engages pre-selected contacts in the array to establish electrical circuits corresponding to the indicia registering with the window;

a push button reciprocally mounted on the housing member; and

means extending between the rim and the other of said member, said means being operatively interconnected between the push button and the cam surfaces to advance the wheel and position the next succeeding indicia in registry with the window as the push button is depressed.

3. A switch of the class described including the combination of:

a housing member having a space therein;

a wheel rotatably disposed in said space;

a peripheral rim on said wheel and including a series of indicia circumferentially spaced around the periphery of the wheel;

a window in said housing member positioned to register with only one of the indicia;

a cover member secured to said housing member and sealing said space;

an annular array of fixed contacts on one of said members, said array including a separate contact for each of the indicia on the wheel;

a movable contact mounted on said wheel and including at least one portion that engages at least one pre-selected fixed contact in the array to establish an electrical circuit corresponding to the indicia registering with the window;

a push button reciprocally mounted on the housing member; and

means extending between said rim and one of said members, said means being operatively interconnected with the wheel and said push button and effective to rotate the wheel and advance the wheel and position the succeeding indicia in registry with the window as the push button is pushed inwardly.

4. A switch of the class described including the combination of:

a housing member having a space therein;

a wheel member rotatably disposed in said space;

a series of indicia circumferentially spaced around the periphery of the wheel;

a window in said housing member positioned to register with only one of the indicia;

a cover member secured to said housing member and sealing said space;

an annular array of contacts on one of said members, said array including a separate fixed contact for each of the indicia on the wheel;

a movable contact mounted on the other of said wheel and including at least one portion that engages at least one pre-selected fixed contact in the array to establish an electrical circuit corresponding to the indicia registering with the window; and

a push button reciprocally mounted on the housing member and operatively interconnected with the wheel member, said push button being effective to rotate the wheel member and advance the next indicia into registry with the window as the push button is pushed inwardly.

5. A switch of the class described including the combination of:

a housing having a side wall member and an edge wall, said edge wall extending around said side wall member and partially enclosing a space;

a wheel rotatably disposed in said space;

a rim extending around the periphery of the wheel, said rim having a width that defines the maximum

- axial dimension of the wheel, said rim including a series of indicia circumferentially spaced there-around;
- a window in said edge wall positioned to register with only one indicia at a time;
- an imperforate cover secured to said edge wall parallel to the side wall member to seal the space and the wheel therein;
- a separate fixed contact on the inside of one of said members for each of said indicia, said contacts being disposed in the space in a circular array coaxial with the wheel;
- a movable contact mounted on the wheel between said wheel and said member, said movable contact being carried by the wheel and including at least one portion that engages a fixed contact corresponding to the position of the indicia; and
- a printed circuit on the inside of cover, said circuit including a separate conductor for each fixed contact, said conductors extending across the inside of the member and between the edge wall, said conductors including externally exposed portions forming a plurality of terminals.
6. A switch of the class described including the combination of:
- a housing member at least partially enclosing a space;
- a wheel rotatably disposed in said space and including an angular rim;
- a plurality of cam surfaces disposed between said rim and the center of said wheel;
- a series of indicia circumferentially spaced around said rim of said wheel;
- a cover member secured to said housing member and enclosing said space and said wheel therein;
- a window in said housing member positioned to register with only one of said indicia at a time;
- an annular array of contacts on one of said members, said array including a separate contact for each one of said series of indicia;
- a movable contact mounted on said wheel and including at least one portion that engages pre-selected contacts in said array to establish electrical circuits corresponding to the indicia registering with said window;
- a push button reciprocally mounted on said housing member;
- a link extending between said rim and one of said members, and operatively connected to said push button; and

5

a washer member operatively interconnected between said cam surfaces and said link, for rotating said wheel and advancing said wheel to position the succeeding indicia in registry with said window as said push button is pushed inwardly.

7. A switch of the class described including the combination of:

- a housing member having a space therein;
- a wheel rotatably disposed in said space;
- a peripheral rim on said wheel and including a series of indicia circumferentially spaced around the periphery of said wheel;
- a window in said housing member positioned to register with only one said indicia;
- a cover member secured as to said housing member and sealing said space;
- an annular array of fixed contacts on one of said members, said array including a separate contact corresponding to each of said indicia;
- a movable contact mounted on said wheel and including at least one portion that engages at least one pre-selected fixed contact in said array to establish an electrical circuit corresponding to the indicia registering with said window;
- a push button reciprocally mounted on the housing member;
- a link extending between said rim and one of said members and operatively connected to said push button; and
- a washer member operatively interconnected with said wheel and said link and effective to rotate said wheel for advancing said wheel to position the succeeding indicia in registry with said window as said push button is pushed inwardly.
